UNITED STATES PATENT OFFICE.

HENRY DE TAMBLE, OF AURORA, ILLINOIS, ASSIGNOR OF THREE-FOURTHS
TO JOHN POULL, OF SAME PLACE, AND LOUIS HALBERSTADT, OF NAPER-
VILLE, ILLINOIS.

VEHICLE-TONGUE TIP.

SPECIFICATION forming part of Letters Patent No. 415,860, dated November 26, 1889.

Application filed September 17, 1889. Serial No. 324,264. (No model.)

To all whom it may concern:

Be it known that I, HENRY DE TAMBLE, a citizen of the United States of America, residing at Aurora, in the county of Kane and State of Illinois, have invented certain new and useful Improvements in Vehicle-Tongue Tips, of which the following is a specification, reference being had therein to the accompanying drawings.

10 This invention relates to the construction and arrangement of the tongue-tip cap for connecting the neck-yoke with the said tongue, with the object in view to provide a strong coupling device for readily connecting or disengaging the neck-yoke ring; and it consists of a braced hook rigidly secured to the tongue-tip, and of a latch pivoted in the tip-cap and resting with its rearward end upon the forward end of the hook, thus closing the 15 same by its own gravity, and thereby preventing the neck-yoke ring from disconnecting, all as will be more fully hereinafter described and specifically claimed.

In the accompanying drawings, Figure 1 represents a sectional elevation of my improved tongue-tip with the neck-yoke in position after coupling the neck-yoke ring; Fig. 2, a similar view of the same with the parts in position while coupling the neck-yoke; 20 Fig. 3, a cross-section on line $x-x$ in Fig. 2, and Fig. 4, a cross-section on line $y-y$ in Fig. 2.

Corresponding letters of reference in the several figures of the drawings designate like parts.

35 A denotes the front end of the wagon-tongue, covered on top and bottom by metal plates B and C, connected in front by a round iron loop D for hitching additional horses. To the bottom of the tongue-tip is secured a hook E, having a shank e extending through holes in plates B and C and through a hole in the tongue, with a shoulder butting against the plate C, and having formed a rivet-head to its upper end against or into a counter-sink of plate B for rigidly tying the plates to the tongue and at the same time rigidly securing the hook thereto. To its rear the hook E has formed a brace f, rigidly secured to plate C by a rivet, which may also be 40 passed through both plates B and C and

through the wagon-tongue. The connecting portion of the hook and brace is sufficiently downwardly projecting for supporting the tongue when lowered to the ground, so as to spare the hook E from being bent or otherwise damaged. Forward of hook E the plate C is slotted and provided with upwardly-extending eye-lugs g, between which is pivotally secured upon a pin h the eyed hub of a latch H, the rearward end of which, by its own gravity, will drop to rest upon the forward portion of hook E, to close such hook automatically when, for connecting the neck-yoke, its coupling-ring I is passed over the end of the wagon-tongue and shifted rearward, whereby it will lift said latch H, allowing the ring I to enter hook E, and then after thus entered will drop again, closing the hook to prevent the disconnecting; and for the purpose that said hook E need not be 55 made too far downwardly extending to provide room for ring I to slide in between said hook E and latch H a notch or concave i is formed in plate C for the end of latch H to enter when turned against such plate C. 75

It will be readily seen that this device is very strong and durable and enables a quick connection or disengaging of the neck-yoke ring.

What I claim is—

The pole-tip A, having secured top and bottom plates B and C, connected by loop D, and in combination therewith the hook E, rigidly fixed against the bottom thereof by its shank e, passed through both plates B and C and riveted on top, and having a rearward brace f, extending from below hook E, to provide a downwardly-projecting heel as a protector to such hook, and the latch H, pivotally secured between eye-lugs g to the upper side of plate C by a pin h, with the pointed rear end of said latch resting upon the forward end of hook E, and entering a recess i of plate C when lifted, all substantially as set forth.

In testimony whereof I affix my signature in presence of two witnesses.

HENRY DE TAMBLE.
